(57) **CLAIM**

The ornamental design of a soldering block for LED tape light, substantially as shown and described.

DESCRIPTION

FIG. 1 is a front view of the soldering block for LED tape light of the present invention;

FIG. 2 is a left side view thereof;

FIG. 3 is a rear view thereof;

FIG. 4 is a right side view thereof;

FIG. 5 is a top view thereof;

FIG. 6 is a bottom view thereof; and,

FIG. 7 is a perspective view thereof.

The stippling in the drawings is meant to convey contours and not a contrast in materials. The stippling forms no part of the claimed design. The areas defined by broken lines form no part of the claimed design.

1 Claim, 4 Drawing Sheets
